J. GRAHEK

MECHANICAL PULLER

Filed Sept. 16. 1921

Inventor
John Grahek.
S. S. Stevens.

Attorney

UNITED STATES PATENT OFFICE.

JOHN GRAHEK, OF CHISHOLM, MINNESOTA.

MECHANICAL PULLER.

Application filed September 16, 1921. Serial No. 501,096.

To all whom it may concern:

Be it known that I, JOHN GRAHEK, a citizen of the United States, residing at Chisholm, in the county of St. Louis and State of Minnesota, have invented certain new and useful Improvements in Mechanical Pullers, of which the following is a specification, reference being had therein to the accompanying drawing.

10 This invention relates to mechanical pullers and has special reference to such a device for the purpose of pulling wheels, gears, pulleys, or the like, from the shaft or axle upon which they are mounted.

15 The principal object of the invention is to provide such a device which is simple in construction and susceptible of a wide range of adjustment for accommodation to various requirements.

20 Other objects and advantages of the invention will appear in the further description thereof.

25 Referring to the accompanying drawing in which like reference characters indicate like parts, and wherein—

Figure 1 is a top plan view of one of the improved pullers;

Figure 2 is a side elevation;

30 Figure 3 is an elevation of a common bolt which may be used in place of the specially designed pulling hooks, and

Figure 4 is a perspective view of one of the latter.

35 1 represents a cross bar, or body portion of the puller which is preferably of narrow oblong shape in plan view, having an enlarged or bossed central portion as at 2 through which is formed an internally screw threaded hole for the reception of the externally screw threaded operating bolt 3.

40 The bolt 3 has a suitably formed head 4 for convenient reception of a common wrench by which it is intended the device may be operated. The opposite end of the bolt is preferably provided with a central tip 5, or slightly rounded or sharpened for engagement against the axle or shaft from which the object is being pulled, such shaft or axle usually being provided with a central depression such as is caused in the process of turning or making of same.

45 In side elevation I prefer to make the cross bar of greater thickness in the central portion, the lower faces of which extend radially therefrom, being inclined as at 6,

while the opposite face of the bar is preferably perfectly straight.

Through the two opposite ends of the bar and parallel with the axial hole thereof are formed elongated slots 7 for cooperative engagement with the pulling hooks or bolts, the especially designed ones of which are illustrated at 8, there being a pair of such hooks for each puller. The object engaging ends of these hooks are preferably of general rectangular form in cross section, are provided with the hook like projection 9 at the extreme free end thereof and taper slightly towards such free end as clearly illustrated in Figure 4 of the drawing. They are also provided with laterally projecting shoulders 10, the uppermost faces of which are slightly inclined to coincide with the inclination of the cross bar, as they are made to impinge same by the tightening of the nuts 11 on the upper cylindrical screw threaded bolt portion 12 of the hooks and which portion is made extendable through the slots 7 in the cross bar. By this structure it is evident that the hooks may be moved either towards or from the central portion of the bar to accommodate different sized gears or wheels being pulled and after being once set to the proper size, for example intermediate of the spokes of the wheel and adjacent the hub thereof, they may be drawn up tightly in such established position on the cross bar before stress is put upon the pulling bolt 3.

45 This feature of my invention is considered important in that it prevents any slipping or springing of the hooks out of position when the pulling is conducted.

50 In Figure 3 I have illustrated a common screw threaded bolt 13 which may be used in place of the hooks 8 which may be desirable in the pulling of gears or wheels which have holes formed in the webs thereof adjacent the shaft upon which they are mounted, when said bolts may be screwed into the threaded holes made for this purpose.

Having thus described my invention, what I claim and desire to secure by Letters Patent, is:

55 A holding member for pullers having a main cross-bar with opposed wholly surrounded slots therethrough, said holding member being cylindrical and externally screw threaded upon that end which is engaged within the slot in the cross-bar, and

2
rectangular upon the opposite end, the latter being hooked for engagement with the object to be pulled, and a shoulder at the junction of the two different shapes of the member, said shoulder projecting principally in the opposite direction to that of the hook to prevent stress upon the latter bending the member backwardly, the longitudi-

nal face of both ends of the member being in the same plane.

In testimony whereof I hereunto affix my signature in the presence of two witnesses.

JOHN GRAHEK.

Witnesses:

S. C. BRONSON,
S. GEO. STEVENS.
